UNITED STATES PATENT OFFICE.

OTTO GEISLER, OF CHICAGO, ILLINOIS.

RIGID AIRSHIP.

Application filed July 26, 1926. Serial No. 125,043.

My invention relates to improvements in airships of the rigid type and it consists in the combinations, constructions, and arrangements herein described and claimed.

5 An object of my invention is to provide an improved mooring device, by means of which an airship may be easily and firmly moored on the water of a lake or stream or the like.

10 A further object is to provide a mooring device which can be manipulated so as to launch the ship easily, the mooring being accomplished without the waste of gas and the launching being accomplished without the
15 waste of ballast.

A further object of my invention is to provide means for scooping up water while the ship is still in motion, thereby causing it to settle down and serving to maintain it or moor it in a lake, in a stream, etc.

20 moor it in a lake, in a stream, etc. A further object is to provide an airship which is an improvement over that set forth in my prior Patent No. 1,550,797, this improvement being particularly directed toward the wings, so as to present a more compact structure without at all decreasing the efficiency of the device.

A further object is to provide a new form of water keel in which the means for scoop-
ing up water are carried.

Other objects and advantages will appear in the following specification, and the novel features of the invention will be particularly pointed out in the appended claims.

35 My invention is illustrated in the accompanying drawings, forming part of this application, in which

Figure 1 is a side view of the airship,

Figure 2 is an enlarged section substantially similar to Figure 1.

40 tially along the line 2-2 of Figure 1,

Figure 3 is a detail view showing the means by which the water scoops are actuated, and

Figure 4 is a detail view of one of the water scoops, showing the connecting cables.

In carrying out my invention I provide

concentric cylindrical members, which are

50 preferably made of duralumin. As will be seen from Figure 1 there is a pair of inner cylinders 1 and 2. These cylinders are spaced apart and are held in spaced relation by means of struts 3, which radiate from a common center 4. Two outer cylinders 5 and 6 are also provided, and these are spaced 55 from the cylinder 2 by the diagonal braces

7, which are secured at their ends by fish plates 8 to the cylinders.

On each side of the body portion which is formed by the concentric cylinders are wings such as that shown in Figure 2. These wings are convex on their tops, as shown at 9, and are concave on their bottoms, as shown at 10. They are preferably made of metal like the cylinders, which form the body portion, and are held in position by means of struts 11, secured to the body portion. In the interior of each wing is a series of tubes 12, these tubes being for the purpose of forming an additional reinforcement for the wings and providing a means for curving the outer portions of the wings into graceful, stream-like form. As will be seen from Figure 1, these tubes 12 are not continuous, but are composed of a series of sections spaced apart. This reduces the weight of the ship, but provides sufficient strength.

The lower portion of the outer cylinders 5 and 6 is flattened as will be seen at 5' and 6'. All of the available space between the concentric cylinders and in the interior of the wings, as well as the interior of the tubes 12, is filled with a light gas, such as hydrogen or helium. 80

Attached to the body portion, which has thus been described, is a frame-work 13, upon which is carried the motors M and the quarters Q for the crew, the ammunition store-houses, etc. The bottom of this frame forms a water keel 14. The propellers P are carried on supports 15. 85 90

The water keel 14 has pivotally connected thereto a mooring hook 16, which may be let down when desired, so as to moor the ship.

In Figure 3 I have shown a series of water scoops 17, which are pivotally mounted at 18 to the bottom of the water keel. Each of these scoops consists of a frame-work 19 of metal, which is covered by a sheet metal covering. 100

The frame-work which runs underneath the airship is provided with a series of electrically operated winches 20. Each of these winches is controlled by an electric motor indicated at Mo and each has a worm connection, so that the speed is reduced, while the power is increased. Extending from the winches 20 are cables 21, there being preferably three for each scoop, as shown in Figure 4. These cables, as will be seen, are attached 100 110

to the front ends of the scoop, so as to swing the latter upwardly. As will be seen from Figure 1 I have provided vertically disposed rudders 22 for horizontal movement, and 5 horizontal rudders 23 for effecting a vertical movement. In addition to this the front and the rear ends of the wings 9 are bevelled, as shown at 24, for assisting in elevating or lowering the ship.

10 From the foregoing description of the various parts of the device, the operation thereof may be readily understood. Let us assume that the ship is cruising in the air. Propellers 22 may be operated so as to guide 15 the ship in a horizontal direction. As long as the ship is proceeding in a horizontal direction, the effect on the upper and lower surfaces of the front of the wings 9 is neutralized, that is to say, there is no tendency 20 to go up or go down. When, however, the horizontal rudders 23 are manipulated; for instance, to swing the rear end of the ship up, that will incline the forward surface 24 still more and tend to swing the forward end 25 of the ship down. When the ship has almost reached the water, the scoops, the forward ends of which have been let down, will catch the water and scoop it up. This will tend to exert a drag on the ship, which will tend to 30 pull the rear end down. As the rear end comes down, the scoops nearer the rear end will then fill until all of the scoops have 35 filled, when the ship will settle on the water and will stay moored. It is, of course, understood that as the scoops are filled with 40 water they are raised by means of the winches to a horizontal position. Thus, without letting out any gas, the ship may be brought down and may be held in moored 45 position. When, now, it is desired to ascend, all that is necessary is to actuate the winches so that the forward end of the scoops are drawn still further upwardly, when the water will pour off of the rear end, and thus the scoops will be emptied. This obviates 50 the necessity of throwing out any other ballast, so that neither gas nor ballast is wasted in the mooring or the launching of the ship.

I claim:

50 1. The combination with an airship of the

lighter than air type, having a keel, of a water scoop hinged to the keel at one end, a power device carried by the keel, and flexible connection from said power device to the front end of said water scoop for raising the latter to a position to retain the water.

2. The combination with an airship of the lighter than air type, having a keel, of a water scoop hinged to the keel at one end, a power device carried by the keel, and flexible connection from said power device to the front end of said water scoop for raising the latter to a position above the rear hinged end of the scoop, whereby the water is discharged over the rear end.

3. A rigid airship of the lighter than air type, comprising an elongated body portion, a water keel carried by said body portion, a plurality of water scooping units carried by the keel, means for independently operating each of said water scooping units and for discharging said units at will.

4. A rigid airship of the lighter than air type, comprising an elongated body portion, a keel carried by the ship, a plurality of water scoops hinged at their rear ends to the keel, means for lowering the front ends of the scoops to scoop up water and for raising the scoops to a horizontal position to retain the water, said raising and lowering means being further operable to raise the front ends of the scoops to a higher position, whereby the water is discharged over the rear of the scoops.

5. The combination with an airship of the lighter than air type having a keel, of a plurality of water scoops pivotally connected at their rear ends to the keel, and means for lowering the front ends of the scoops to scoop up water and for raising the scoops to a horizontal position to retain the water.

6. The combination with an airship of the lighter than air type having a keel, of a plurality of water scoops pivotally connected at their rear ends to the keel, and individual means for lowering the front ends of each of the scoops to scoop water up and for raising the scoops to a horizontal position to retain the water.

OTTO GEISLER.
